UNITED STATES PATENT OFFICE.

IRWIN G. BURTON, OF LOS ANGELES, CALIFORNIA.

FLAGSTAFF-HOLDER FOR AUTOMOBILES AND THE LIKE.

1,266,770.

Specification of Letters Patent. Patented May 21, 1918.

Application filed April 3, 1917. Serial No. 159,434.

To all whom it may concern:

Be it known that I, IRWIN G. BURTON, a citizen of the United States, residing at Los Angeles, in the county of Los Angeles and State of California, have invented new and useful Improvements in Flagstaff-Holders for Automobiles and the Like, of which the following is a specification.

This invention relates to a flag mounting and particularly pertains to means whereby a flag may be mounted upon the radiator cap of a motor vehicle.

It is the principal object of this invention to provide a simple attachment adapted to be mounted upon the radiator cap of a motor vehicle and which will provide means for detachably supporting the staff of a flag.

Another object of this invention is to provide positively acting means for gripping the flag staff and thereby insuring against its loss.

Another object of this invention is to provide a flag mounting which may be disposed in a concealed position when not in use and which will close the opening through the radiator cap.

It is a further object of this invention to provide a mounting of the above character which is simple in its construction, may be mounted without difficulty upon a radiator cap, and without requiring a new or specially constructed cap.

Other objects will appear hereinafter.

The invention is illustrated, by way of example, in the accompanying drawings in which:

Figure 1 is a fragmentary view of the hood and radiator of an automobile, disclosing a flag mounted upon the radiator cap thereof.

Fig. 2 is an enlarged view in vertical section illustrating the radiator cap as fitted with the flag mounting and particularly disclosing the flag staff positioned therein.

Fig. 3 is a view in elevation with parts broken away to disclose the disposition of the flag mounting when it is not in use.

Referring more particularly to the drawings, 10 indicates a case of a radiator which is provided with a neck 11. This neck extends upwardly from the top of the radiator case and is normally closed by a cap 12 which is here shown as a mounting for a flag 13. Referring particularly to Fig. 2 of the drawings, it will be seen that the radiator cap is formed with a threaded

sleeve 14 and a top portion 15, both of which are of common construction. The top 15 of the cap is prepared by forming a straight cylindrical bore 16 through it. This bore 60 is adapted to receive the sleeve 17 of the flag mounting. This sleeve is formed with an opened end 18 which is exteriorly threaded and has longitudinal slots 19 extending along its sides to permit a lock-nut 20 to 65 wedge the side walls of the sleeve around the staff 21 of the flag 13. The threads upon the end 18 of the sleeve are tapered as is common in pipe thread construction and it will be understood that threads of the same 70 design are formed within the nut so that tightening of the nut will contract the walls of the sleeve. The opposite end of the sleeve is closed and is exteriorly threaded to receive a cap 22 provided for a purpose which 75 will be hereinafter disclosed. A threaded length 23 is formed along the body of the sleeve 17 and is adapted to receive a lock-nut 24.

When a flag is to be mounted within the 80 sleeve 17, the sleeve is passed through the opening 16 in the radiator cap, with the split end 18 extending upwardly through the cap. The staff of the flag is positioned within the sleeve and is thereafter secured 85 in fixed relation thereto by tightening the nut 20 down upon the threaded end of the sleeve. After the staff has been securely wedged in place, the nut 24 is tightened up against the under face of the radiator top 90 15 and will cause the sleeve to be fixedly held. The flag will be thus maintained as shown in Fig. 1 of the drawings.

When the sleeve is not required, the flag is removed and the nut 20 taken from the 95 end of the sleeve to permit the removal of the sleeve, after which the nut is placed in position again and the end cap 22 removed. The sleeve is then inverted and its closed end positioned to extend upwardly 100 through the radiator cap, after which the end cap is placed in position and the sleeve locked by the nut 24. This will close the opening in the radiator cap and also lend a finished appearance thereto without disclosing the opened end of the sleeve within which the flag staff is adapted to seat.

It will thus be seen that the flag mounting here disclosed is simple in construction and that it may be readily adapted for use 110 upon most radiator caps and will positively hold a flag in position therein. It is also

evident that this identical mounting may be placed at other points upon the vehicle if desired.

While I have shown the preferred construction of my flag mounting as now known to me, it will be understood that various changes in the combination, construction, and arrangement of parts may be made by those skilled in the art without departing 10 from the spirit of my invention.

I claim:

1. In a flag mounting, the combination with a radiator cap having a central opening formed through it, of a tubular sleeve 15 adapted to extend through said opening and to receive the end of a flagstaff, means whereby said staff may be detachably secured within the sleeve, locking means for

securing the sleeve within the opening through the cap, and means whereby the 20 opening through the radiator cap may be closed in a slightly manner when the staff is removed.

2. In a flag mounting, the combination with a radiator cap having a central opening through it, of a split tubular sleeve 25 adapted to extend through said opening and receive the end of a flagstaff, a jam nut to clamp the sleeve upon the staff, and a clamping nut acting in combination with the jam 30 nut to hold the sleeve in position in the cap.

In testimony whereof I have signed my name to this specification.

IRWIN G. BURTON.
